COLLAR ASSEMBLY FOR SHIRTS

Joseph W. Less, Clinton, Iowa

Application March 28, 1950, Serial No. 152,348

12 Claims. (Cl. 2—132)

1

This invention relates to shirt collars and particularly to a shirt collar assembly including novel means for supporting, stiffening and shaping the collar wings.

In order to position the wings of shirt collars, it is now common practice to employ various detachable mechanical clips and pins which are often difficult to apply to the collar, tend to become disengaged accidentally during wearing, and are frequently visible when used. The present invention is applicable to turn-down collars generally, and provides in association with such collars novel elements which, though completely hidden by the collar, perform the functions of the objectionable mechanical devices heretofore used.

For purposes of clarity, the term collar wing will be used hereinafter to refer to that portion of the end of a turn-over collar which constitutes a scalene triangle, the base lying on the fold line of the collar assembly, the shorter side constituting the collar end, and the longer side extending from the apex of the collar point to the base, the size of the angle at the apex of the triangle being determined by the shape of the collar wing point. Though it may seem that this is an arbitrary definition, it will be obvious that it is this portion of each end of the collar band which tends to become misshapen when turn-over collars are worn.

The invention is directed particularly to a collar assembly comprising a neck band, a turn-over collar band terminating at each end in a wing of the type just described and joining the upper edge of the neck band along a fold line, and a novel supporting and shaping element positioned beneath each wing of the collar. Each supporting and shaping element includes a body portion in the shape of a scalene triangle, the body portion being secured at its base to the neck band. Each supporting and shaping element further includes an extension directed rearwardly along the neckband from the longer side of the triangular body portion, the extension being directed at such an angle that it extends across the fold line between the neck band and collar band when the collar assembly is unfolded. When the collar band is folded down and the supporting and shaping elements thus lie between the collar band and neck band, the extensions on each of said elements must be slightly displaced angularly to lie beneath the fold line between the collar band and the neck band. It will be seen from the more detailed discussion that follows that this slight pivoting of the extensions, coupled with the curving of the extensions along the neck

2

band when the collar is buttoned about the neck of the wearer, causes the supporting and shaping elements to assume a convex shape, which shape is imparted to the collar wings overlying the supporting and shaping elements.

Though the invention operates with particular efficiency when employed with a turn-down collar worn with a necktie, the invention also serves to improve the appearance of such a collar when worn open without a necktie.

In order that the invention may be more readily understood in detail, reference is had to the accompanying drawings, which form a part of this specification, and wherein:

15 Fig. 1 is a plan view of a portion of a collar assembly including a collar wing supporting and shaping element in accordance with the invention, the collar assembly being illustrated as unfolded to lie substantially in a single plane;

20 Fig. 2 is a perspective view of a complete collar assembly of the type shown in Fig. 1, the collar wing supporting and shaping elements being shown in dotted lines;

Fig. 3 is a vertical sectional view taken on the line 3—3, Fig. 2;

25 Fig. 4 is a diagrammatic view of the collar wing supporting and shaping element shown in Fig. 1, illustrating the relative positions of the supporting and shaping element, its rearwardly directed extension, and the fold line of the collar assembly;

30 Fig. 4a is a diagrammatic view similar to Fig. 4 but showing a modified form of extension for the collar wing supporting and shaping element;

35 Fig. 4b is a diagrammatic view similar to Fig. 4, but showing a second modified form of extension;

Fig. 5 is a perspective view illustrating the shape assumed by the collar wing supporting and shaping element when the collar assembly is buttoned about the neck of the wearer;

40 Fig. 6 is a plan view similar to Fig. 1, but showing a modified form of collar wing supporting and shaping element secured to the neck band of the collar assembly by separable snap features;

45 Fig. 7 is a vertical section taken on the line 7—7, Fig. 6, with the snap fastener elements spaced slightly apart;

Fig. 8 is a plan view similar to Fig. 1, illustrating one manner in which the point of the collar wing supporting and shaping element may be secured to the collar wing;

Fig. 9 is a plan view similar to Fig. 1, illustrating a further modification of the invention; and

55 Fig. 10 is a perspective view of a complete collar assembly of the type shown in Fig. 9, the

collar being shown in the position assumed when worn open at the neck, a portion of the collar band being shown as broken away to illustrate the position of various elements of the invention.

Referring now to the drawings, and first to Fig. 1 thereof, it will be seen that the collar assembly here shown includes a neck band 1 joined along a fold line 2 to a turn-down collar band 3. The collar band 3 terminates at each end in a pointed wing 4, only the right end of the collar assembly being shown. Positioned adjacent the under side of the collar wing 4 is a supporting and shaping element 5 which, as will be more fully discussed hereinafter with reference to Fig. 4, is generally triangular in shape and somewhat smaller than the collar wing 4.

The element 5 is secured at 6 in any suitable manner to the neck band 1, so that the base of the triangle of the element 5 is anchored at a point either coinciding with or closely adjacent to the fold line 2. In this embodiment of the invention, in which the wing supporting and shaping elements are adapted to be secured in place when the collar assembly is manufactured, I have shown the element 5 as including a tab 7 which, as is shown more clearly in Fig. 3, is secured between the two fabric plies which constitute the neck band 1, and it will be understood that the tab 7 may be locked in place by stitching or by being otherwise secured to the two fabric plies of the neck band. It will be noted that the normal shape of the element 5 is such that, with its base anchored at 6 to the neckband, the apex 8 of the element is offset slightly toward the center of the collar from the apex 9 of the collar wing 4.

The element 5 also includes an extension 10 directed toward the center of the collar at an angle to the fold line 2 such that, when the collar assembly is unfolded as shown, the extension 10 lies across the fold line 2. In the present embodiment, the extension 10 is shown as being generally rectangular. But, the extension may be of a different shape, so long as its length, and the angle at which it is disposed relative to the fold line 2, are such that the extension lies across the fold line 2 when the collar is unfolded.

The collar wing supporting and shaping element 5, including its extension 10, is fabricated from a material which, though flexible, is preferably stiffer than the material of the collar band 3. The main body of the element and its extension are preferably fabricated as an integral unit from a single sheet of such material.

Referring now to Fig. 4, it will be seen that the collar wing supporting and shaping element provided by the invention may be described as comprising a main body portion which has the general form of a scalene triangle defined by base 14, a shorter side 15 corresponding to the end of the collar band, and a longer side 16 extending across the collar band and joining the shorter side 15 at the apex 8. It will be noted that the triangular body portion of the collar wing supporting and shaping element is somewhat smaller than the scale triangle of the collar wing as hereinbefore defined. The extension 10 slants from the long side 16 of the triangle toward and across the fold line of the collar assembly. Since the base 14 of the body portion of the element substantially coincides with the fold line of the collar assembly, it will be noted that the extension 10 may also be said to extend beyond the base line of the triangular

body portion. It will also be noted that the longitudinal center line of the extension 10 intersects the longer side 16 at the point X and defines with the longer side 16 an acute angle α . When the collar band is folded down against the outside of the neck band, the extension 10 must be angularly displaced to bring the extension beneath the fold line. Since the main body of the element 5 is anchored along its base 14 to the neck band 1, such displacement of the extension 10 tends to force the side 16 of triangular portion of element 5 toward the end of the collar, shifting the apex 8 into line with the apex of the collar wing. Pressure applied to the body portion of the element 5 by pivotal displacement of the extension 10 tends to distort the body portion out of its normal flat plane, since it is anchored to the neck band at the base 14. If the element 5 and its extension 10 are in a single plane at the time of pivotal displacement of the extension 10, the resulting compression may distort the supporting and shaping element into either a convex or a concave form. But when the collar is being worn, the extension 10 is held between the collar band and the neck band, and therefore follows the curve of the neck band rearwardly along the wearer's neck. Curving of the extension 10 along the neck of the wearer causes the generally triangular body portion of the element to assume a convex shape, instead of a concave shape, under the compression applied to that portion by the pivotal displacement of the extension 10 relative to the fold line 2. By stating that the body portion of the element assumes a convex form, I mean that it bulges outwardly from the neck band. It will be noted that the extensions 10, as more clearly seen in Fig. 2, terminate at the side of the neck of the wearer when the collar assembly is worn. If the extensions 10 are made too long, and extend beyond the side of the neck, approaching the back of the collar, downward displacement of the extension will result only in lateral distortion of the extensions themselves, and will not result in compression of the body portions of the collar wing supporting and shaping element.

Thus, for the collar wing supporting and shaping element to assume a convex shape when the collar assembly is buttoned about the wearer's neck, it is necessary that the generally triangular body portion of that element be anchored substantially at its base, that the extension 10 lie at an angle to and extend somewhat across the fold line 2 of the collar assembly when the collar is unfolded, and that the extension 10 be so situated as to conform to the curve of the neck band when the collar assembly is worn. I do not wish to infer that the specific shape and arrangement of the extension shown in Fig. 4 must be adhered to. As shown in Fig. 4a, the invention may include a generally triangular body portion 5a, and an extension 10a which joins the longer side of the triangular portion 5a at a point substantially above the base 14a. Further, as shown in Fig. 4b, the extension 10b may be sufficiently wide that the entire long side of the triangular portion 5b is joined to the extension. The particular shape chosen will depend mainly upon the stiffness of the material employed.

Fig. 5 illustrates the shape assumed by the collar wing supporting and shaping element when the collar assembly just described is worn. Here, 75 it will be seen that the main body of the element

5

5 is distorted into convex shape and lies beneath and in substantial alignment with the collar wing 4. The extension 10 is maintained in displaced position, causing the distortion of the main body of the element 5, because the side 7 of the extension bears against the fold line 2. It will also be seen that, in this position, the extension 10 follows the curve of the neck band, being held thereagainst by the turned down collar band 3. The base 14 of the generally triangular collar wing supporting and shaping element 5 is preferably coincident with a sharp fold line in the relatively stiff material of that element. This fold is preferably made to define a dihedral angle more oblique than the angle between the collar band 3 and the neck band 1 when the collar is worn, so that the element 5 presses outwardly against the wing of the collar. Also, the distorting effect produced by displacement of the extension 10 when the collar is turned down tends to force the supporting and shaping element into engagement with the under side of the collar wing, and the convex shape of the element 5 is therefore imparted to the collar wing.

As has been stated with reference to Fig. 3, the neck band 1 may be fabricated from two separate plies of fabric, and the tab 7 of the element 5 may then be inserted between the two plies of the neck band and there secured by any suitable means to anchor the base of the element 5. The same result may be obtained by the use of one or more snap fasteners, as is shown in Figs. 6 and 7. Here, a modified form of collar wing supporting and shaping element is shown comprising a generally triangular main body 20 having a base 21 constituting a fold line or crease between the main body 20 and a securing tab 22. The securing tab 22 is provided with snap fastener elements 23 and 24 arranged to engage matching elements secured to the outer surface of the neck band 1, as is illustrated in Fig. 7. The collar wing supporting and shaping element also includes an extension 25, Fig. 6, which is generally lobe shaped and slants rearwardly from the main body 5, extending across the fold line 2 between the neck band and the collar band when the collar assembly is unfolded. The two snap fasteners serve to anchor the base of the collar wing supporting and shaping element to the neck band 1 along the base of the main body 20. When the collar assembly is to be worn, the collar 3 is turned down and the extension 25 is simultaneously displaced until the lower portion 26 thereof engages the fold line 2. The effect of displacement of the extension 25 is the same as previously described with reference to Figs. 1-5. Whether the snap fasteners illustrated in Figs. 6-7 are used, in place of a permanent means for attaching the collar wing supporting and shaping element, will depend upon whether it is desirable, because of the nature of the material chosen for that element, to remove the element before laundering the collar assembly. It will be obvious that a single snap fastener may be used, since the length of the base of element 20, which bears against the fold line 2, is sufficient to prevent pivoting of the element.

When the collar band 3 is of a particularly soft material, it may be desirable to secure the shaping and supporting element, near its apex, to the under surface of the collar wing. One means for accomplishing this result is illustrated in Fig. 8, where a collar wing supporting and shaping element 35 generally similar to the element 5, Fig. 1, is shown, the base of the main

6

body of the element 35 being anchored to the neck band by a tab 37 in the manner previously described with reference to Fig. 3. The element 35 includes an extension 40 which, as in the case of extension 10, Fig. 1, lies across the fold line 2 when the collar assembly is unfolded, and is adapted for displacement about the point Y' to distort the main body of the element 35 into convex form. The main body of the element 35 is provided with a slit 48 extending from the region of the apex of the element 35 at a slight angle to the center line 49 of the collar wing 4. A button 50 is attached to the under surface of the collar wing 4 and is inserted through the slit 48, as illustrated, thus securing the element 35, in the general region of its apex, to the under surface of the collar wing. The slit 48 is preferably located at the angle shown to accommodate the slight movement of the apex of the element 35 resulting when the extension 40 is displaced to bring the edge 47 thereof into abutment with the fold line 2.

In Fig. 9 there is shown a further embodiment of the invention which not only serves to support and shape the wings of a collar when worn buttoned at the neck, but also functions to better position the collar wings when the collar is worn unbuttoned. As shown in Fig. 9, this embodiment of the invention is again applied to a turn-down collar comprising a neck band 101, the upper edge of which is joined along the fold line 102 to a collar band 103 terminating at each end in a wing 104. This embodiment of the invention embraces a wing supporting and shaping unit 30 comprising an elongated, generally rectangular attaching member 107, a wing supporting and shaping element 105 and a distorting extension 110.

The attaching or anchoring member 107, the element 105 and the extension 110 are formed as an integral unit from a single piece of flexible sheet material which is relatively stiffer than the material of the collar band 103. The wing supporting and shaping element 105 is generally in the form of a scalene triangle, the base 106 of which constitutes a fold line between the element 105 and the member 107.

The extension 110, which serves the purpose of imparting a convex shape to the element 105 when the assembly is worn, is formed integrally with the element 105, extending from the longer side thereof to terminate beyond the fold line 106 and within the limits of the elongated attaching member 107. Thus, a portion of the extension 110 is actually cut from the material of the member 107 and, though this portion of the extension will lie within the limits of the member 107 when the unit is unfolded to lie flat, the extension is free for lateral displacement from the member 107 when the unit is folded about the fold line 106.

The member 107 is attached to the neck band 101 by means of a separable fastener element 111, which may, for example, be either the male or female member of a conventional snap fastener. Secured to the member 107 by the separable fastener element 111 is a stiffening member 112 provided to prevent the material of the member 107 from breaking down with repeated use. The stiffener 112, which may be of a suitable material such as cellulose acetate sheeting or other sheet material substantially stiffer than the member 107, is preferably relatively narrow and extends transversely of the member 107, terminating short of the fold line 106. The stiffen-

ing member 102 preferably terminates substantially at the intersection between the fold line 106 and the longer side of the element 105.

The wing supporting and stiffening element 105 is positioned, as shown, with its shorter side adjacent the end of the neck band 101. Since the base of the element 105, that is, the fold line 106, is materially shorter than is the attaching or anchoring member 107, the member 107 therefore extends rearwardly beyond the element 105. In the present embodiment of the invention, it is preferable that the member 107 be sufficiently long to terminate beyond the extension 110, thus providing a portion 113 lying closely adjacent to the fold line 102 between the collar band 103 and the neck band 101.

In Fig. 9, the extension 110 has been shown as extending along the entire length of the longer side 116 of the element 105. But, it will be understood that it is not necessary that this be true, and that the extension may be narrower if desired, as indicated by the dotted line 118.

Fig. 10 illustrates in wearing position a collar assembly of the type just described. The collar band 103 is turned down, and the element 105 is accordingly folded down about the fold line 106. As previously described herein with reference to Figs. 1-5, the extension 110 is displaced so that the lower edge 117 thereof lies against the fold at 102, this displacement, and the fact that the extension 110 is curved along the neck of the wearer, deforming the supporting and shaping element 105 into a convex form. In Fig. 10, the element 105 and the extension 110 have been broken away to illustrate the position of the attaching member 107.

When the collar assembly shown in Fig. 10 is buttoned at the neck, the convex shape of the elements 105 is imparted to the collar wings 104, in the manner previously described with reference to Fig. 2. When the collar assembly is worn open at the neck, the extensions 110, tending to return to their normal position but being restrained therefrom because the collar band is turned down, cause the collar points to spread apart, giving the appearance of a shirt designed for open collar wear.

Since the anchoring or attaching members 107 are each secured to the neck band 101 at only a single point by the separable fasteners 111, it is necessary to provide against rotation of the entire collar wing supporting and shaping unit around the separable fastener when the collar assembly is worn open at the neck. In the present modification, portions 113 of the attaching members 107 serve this purpose by engaging the fold line 102.

I claim:

1. A collar wing supporting and shaping unit comprising a generally rectangular anchoring member; means for securing said anchoring member to a neck band of a shirt; a collar wing supporting and shaping element in the form of a scalene triangle, said element and said anchoring member being fabricated from a single piece of flexible sheet material and the base of said triangular element constituting a fold line between said element and said anchoring member; an extension formed integrally with said element and extending from the longer side of said element and terminating beyond the base of said element, and a stiffening element secured to and overlying said anchoring member, said stiffening element extending transversely of said member and terminating short of said fold line.

2. A collar wing supporting and shaping unit comprising an elongated anchoring member of sheet form; a collar wing supporting and shaping element generally in the form of a scalene triangle with the base of the triangle being substantially shorter than the length of said anchoring member, said anchoring member and said element being fabricated from a single piece of flexible sheet material and the base of said element constituting a fold line between said element and said anchoring member; an extension formed integrally with said collar wing supporting and shaping element and extending from the longer side of said element, said extension terminating beyond said fold line, and a stiffening element secured to and overlying said anchoring member, said stiffening element terminating short of said fold line.

3. A collar wing supporting and shaping unit comprising an elongated anchoring member of sheet form; a collar wing supporting and shaping element generally in the form of a scalene triangle with the base of the triangle being substantially shorter than the length of said anchoring member, said anchoring member and said element being fabricated from a single piece of flexible sheet material and the base of said element constituting a fold line between said element and said anchoring member; an extension formed integrally with said collar wing supporting and shaping element and extending from the longer side of said element, said extension terminating beyond said fold line; a separable fastener element secured to said anchoring member for attaching said anchoring member to a neck band, and a stiffening element for said anchoring member, said stiffening element being secured to said anchoring member by said fastener element and overlying said anchoring member but terminating short of said fold line.

4. A collar wing supporting and shaping unit constructed in accordance with claim 3, wherein said stiffening element extends transversely of said anchoring member, has a width substantially less than the length of said member, and terminates short of said fold line substantially at the intersection of the longer side and the base of said stiffening element.

5. A shirt collar assembly comprising a neck band, a collar band joining the upper edge of said neck band along a fold line, said collar band terminating at each end in a pointed wing, and a pair of wing supporting and shaping units for the wings of said collar band, each of said units being fabricated from a single piece of flexible sheet material substantially stiffer than said collar band and comprising an elongated anchoring member secured to and overlying said neck band; a wing supporting and shaping element in the general form of a scalene triangle, the base of said triangle constituting a fold line between said element and said anchoring member and being materially shorter than the length of said anchoring member, the short side of said element terminating adjacent the neck band end so that said anchoring member extends rearwardly along said neck band beyond said supporting and shaping element; and an extension formed integrally with said element and extending from the longer side of said element beyond the base thereof to terminate within the limits of said anchoring member when said collar assembly is unfolded to lie flat but being free for lateral displacement from said anchoring member when said collar band is turned down, the fold line between said

supporting and shaping element and said anchoring member being closely spaced below the fold line between said collar band and neck band and extending parallel therewith, and said supporting element having its apex displaced rearwardly from the apex of the corresponding collar wing when said collar assembly is unfolded to lie flat.

6. A shirt collar assembly comprising a neck band, a collar band joined to the upper edge of said neck band along a fold line, said collar band terminating at each end in a pointed wing, and a pair of flexible collar wing supporting and shaping elements adapted to underlie the wings of said collar band when the collar assembly is worn, each wing supporting and shaping element including a body portion in the form of a scalene triangle smaller than the corresponding collar wing and secured to said neck band at the base of the triangle, each wing supporting and shaping element also including an extension formed integrally with said body portion and extending from the long side of the triangle thereof rearwardly across the fold line between the neck band and collar band when the collar assembly is unfolded by being free to move relative to said collar assembly, whereby each extension can be displaced downwardly to lie against the collar fold line when the collar assembly is worn, said extensions terminating at the side of the neck of the wearer when said collar assembly is worn.

7. A shirt collar assembly comprising a neck band, a collar band joining the upper edge of said neck band along a fold line, said collar band terminating at each end in a pointed wing, and a pair of flexible collar wing supporting and shaping elements adapted to underlie the wings of said collar band when the collar assembly is worn, each wing supporting and shaping element including a body portion in the form of a scalene triangle smaller than the corresponding collar wing and secured to said collar assembly along substantially the entire base of the triangle, each wing supporting and shaping element also including a second portion formed integrally with the body portion thereof and extending rearwardly from the long side of the triangle of said element across and at an angle to the fold line of the collar assembly when the same is unfolded but being free to move relative to said neck band and said collar band, whereby when said collar band is turned down said record portion of each element can be pivoted downwardly to abut the fold line between said collar band and said neck band, thereby compressing the body of the element and forcing the same to assume a convex shape when the collar is buttoned.

8. A shirt collar assembly constructed in accordance with claim 7, wherein the body portions of said wing supporting and shaping elements are centrally weakened.

9. A shirt collar assembly comprising a neck band, a collar band joining the upper edge of said neck band along a fold line, said collar band terminating at each end in a pointed wing, a pair of flexible collar wing supporting and shaping elements adapted to underlie the wings of said collar band when the collar assembly is being worn, each wing supporting and shaping ele-

ment including a body portion in the form of a scalene triangle smaller than the corresponding collar wing, and a pair of anchoring tabs for securing said wing supporting and shaping elements to said neck band, each of said wing supporting and shaping elements joining one of said tabs continuously along a fold line constituting the base of the triangle of said element, each of said wing supporting and shaping elements also including an extension integral therewith and slanting rearwardly and upwardly from the long side of the triangle of said element across the fold line of said collar assembly but being free to move relative to said neck band and said collar band, whereby when said collar band is turned down said extension of each element can be pivoted downwardly to lie against the fold line between said collar band and said neck band, thereby compressing the body of the element and forcing the same to assume a convex shape when the collar is buttoned.

10. A collar assembly constructed in accordance with claim 9, wherein the anchoring tab of each collar wing supporting and shaping element is secured to said neck band by at least one separable fastener.

11. A collar assembly constructed in accordance with claim 9, wherein said body portions of said collar wing supporting and shaping elements are centrally weakened.

12. A shirt collar assembly comprising a neck band, a turn-down collar band terminating at each end in a pointed wing and joining the upper edge of said neck band along a fold line, a collar wing supporting and shaping element positioned beneath each wing of said collar band, each of said collar wing supporting and shaping elements being secured at its base to said neck band and being smaller than the corresponding collar wing, and an extension formed integrally with each of said collar wing supporting and shaping elements and extending rearwardly therefrom, said extensions terminating at the side of the neck of the wearer when said collar assembly is worn, each of said extensions being disposed at an angle to said fold line such that, when said collar assembly is unfolded to lie substantially in a single plane, said extensions cross said fold line, each of said wing supporting and shaping elements including its extension being formed as an integral unit from flexible sheet material, said extensions each being displaced downwardly between said collar band and said neck band by abutment with thirdohuuuzvisashrlutaoi by abutment with said fold line when said collar is turned down, whereby said wing supporting and shaping elements are compressed and forced to assume a convex shape when the collar is buttoned.
